UNITED STATES PATENT OFFICE.

EDGAR B. HOOVER, OF PASCO, WASHINGTON.

ORE-SEPARATOR.

1,317,790.

Specification of Letters Patent.

Patented Oct. 7, 1919.

Application filed October 29, 1918. Serial No. 260,086.

To all whom it may concern:

Be it known that I, EDGAR B. HOOVER, a citizen of the United States, residing at Pasco, in the county of Franklin and State 5 of Washington, have invented certain new and useful Improvements in Ore-Separators, of which the following is a specification.

This invention relates to ore separators and has for its object to provide a means 10 whereby the saving of fine gold may be accomplished, *i. e.*, by separating the black sand and fine gold from the lighter sand and gravel.

With this and other objects in view the 15 invention consists of certain novel combinations and arrangements of parts as will be hereinafter explained.

That the invention may be better understood reference is had to the accompanying 20 drawings, in which—

Figure 1 is a side elevation;

Fig. 2 is a partial plan, with drum and revolving griddle removed; and

Fig. 3 is a sectional view.

25 Referring specifically to the drawings the numeral 1 represents the sluice box which is substantially braced by the corner braces 2 extending throughout the length of the sluice box and on either side thereof, and so 30 placed as to provide a channel 3 between the braces.

The upper or inner surfaces of the corner braces are curved at 4 to conform to the radius of the griddle, to be hereinafter explained, and supports the false bottom.

35 This false bottom 5 may be of any suitable material having an exceedingly fine mesh, preference is given, however, to a material having a woven structure.

40 Riffles 6 rest upon the false bottom and are suitably and removably fastened thereto, or through the false bottom to the corner braces 2, and may extend partly up the sides of the sluice box; the height to which they 45 extend being determined by the volume of matter passing through the machine, and by the volume of water available where water is used.

The riffles are preferably spaced uniformly and are curved to conform to the curvature of the false bottom and corner braces, with the inner edge concentric with the outer edge.

50 A drum 7 is revolvably mounted on the sluice box 1 and a spiral griddle 8, formed preferably of radially disposed rods, en-

circles the drum. This griddle 8 while preferably composed of rods, may be composed of any suitable material, such, for instance, as expanded metal and the like, it being essential however that a griddle be formed therewith whose interstices are relatively small; about $\frac{1}{16}$ inch in width being preferred.

That part of the griddle operating over 65 the curved riffles 6 is recessed at 9 to accommodate the riffle, thus bringing the edge of the griddle in close proximity with the false bottom 5 and the riffle 6 without destroying the uniformity of the griddle 8. I 70 use a spiral griddle as this form gives a continuous screening to the mass and tends to move the mass toward the discharge end of the sluice box.

In use the machine is set convenient to the 75 gravel to be operated upon and power from any suitable source is supplied to the griddle. The gravel is then fed in one end of the machine and while great success may be obtained without the use of water, water where 80 available is advised and when used is fed into the machine with the gravel: the griddle now acts as a continuous screen and a conveyer, forcing the waste material to the outlet and screening as it moves resulting in 85 the concentrates being left in the bottom being retained by the riffles.

As above mentioned the false bottom 5 is of a woven structure; as water will percolate through the false bottom, carrying the exceptionally fine particles with it, provision is left between the corner braces 2 for a channel 3 through which the percolations may pass to the outlet end where they may be caught by any suitable means. As this feature is used only in rare cases where the gold is of the fineness of flour and where water is available, and as any means may be employed for collecting the concentrates the specific means used for such collections will 100 not be shown in the drawings.

Since a light current of water will carry off fine gold, provision must therefore be made to break up any current as it passes through the machine. This is accomplished by the 105 griddle in conjunction with the riffles: as the current of water flows through the sluice box the griddle being made up of small or narrow interstices, chops or combs the water, changing the direction of flow of part of 110 the water so that it with the lighter sand and gravel flows over the upper end of the

PATENT SPECIMEN

riffles, while the balance of water with the black sand and gold flows against the riffles which completes the breaking up of the current.

5 The water now together with the concentrates has such a low velocity that the concentrates fall to the false bottom and lodge against the riffles from whence they are subsequently recovered. During this action any 10 flour gold which may percolate through the false bottom will find its way to the channel 3 as above mentioned.

15 In cleaning up, the riffles are removed and the concentrates are gathered in any convenient manner after which the riffles are returned to place and the operation resumed.

If desired a copper plate coated with 20 quicksilver may be added to the false bottom or at the outlet end thereof to catch any waste gold although repeated trials have shown this to be unnecessary.

Having thus described my invention, I claim:

1. In an ore separator, a sluice box, a 25 pervious curved false bottom within the sluice box, curved riffles within and resting upon said false bottom, and a revolving griddle revolvably mounted upon the sluice box and operating within the curved false bottom, said griddle having a portion shortened to register with and operate above the riffles.

2. In an ore separator, a sluice box, a 30 pervious curved false bottom within the sluice box, said false bottom being positioned 35

accurately by supporting members, said supporting members extending longitudinally and continuously of the sluice box on either side thereof, a channel beneath said false bottom, curved riffles within and resting upon said false bottom, and a revolving griddle revolvably mounted on the sluice box and operating within the false bottom.

3. In an ore separator, a sluice box, a pervious curved false bottom within the 45 sluice box, said false bottom being positioned accurately by supporting members, said supporting members extending longitudinally and continuously of the sluice box, and on either side thereof, said supporting members 50 forming with the bottom of the sluice box a channel, said channel beneath the said false bottom and extending longitudinally thereof, riffles within and resting upon the said false bottom, and a revolving griddle mounted on the sluice box and operating within the false bottom.

4. In an ore separator, in combination with a curved sluice box, having curved 60 riffles, a griddle revolvably mounted on the sluice box, said griddle being of the nature of a comb and comprised of a shaft, spirally disposed and radially extending teeth on the shaft, interstices between the teeth sufficient to pass nothing larger than sand, and a portion of said teeth shortened to register with and operate above said riffles.

In testimony whereof I affix my signature.
